TYPOGRAPHICAL COMPOSING MACHINE

Richard Henry Scott, Enfield, and William Fairall Gorse and Arthur Staniland Hayward, Altrincham, England, assignors to Linotype and Machinery Limited, London, England, a limited-liability company of Great Britain

Application February 9, 1940, Serial No. 318,048
In Great Britain February 18, 1939

24 Claims. (Cl. 199—45)

This invention relates to typographical composing machines, such as those known under the registered trade-mark "Linotype." More particularly the invention relates to machines provided with a column of superposed magazines adjustable columnwise to bring a selected magazine into operative relationship with the assembling and distributing mechanisms, and wherein individual magazines may be removed and replaced, for which purpose the magazine column structure includes a base frame appropriate to each magazine.

For effecting the removal of a magazine from such a column in one constructional form of apparatus, after the magazine column has been adjusted to bring the magazine in question into the operative position, the magazines are spread apart, if necessary, to facilitate the handling of the magazine to be removed, and extensible arms mounted on side frames between which the column is adjustable, are moved into extended position to support the magazine during removal.

The object of the invention is to provide an improved form of mechanism associated with such extensible arms, whereby the manipulations preparatory to a magazine change are simplified. To this end the invention contemplates an arrangement wherein the adjustment of an extensible arm to the magazine supporting position serves to actuate means for spreading the magazines where necessary, and means for separating from its base frame the magazine to be removed. The invention also contemplates means whereby the movement of the magazine column to bring a selected magazine to the removal position serves to connect the operating devices of the spreading and separating means with the selected magazine.

Preferably the spreading and separating movements are carried out successively by mechanisms actuated from the same source and the arrangement is advantageously such that a magazine cannot be lifted from its base frame until the magazine frames have been separated. The machine may also incorporate a device whereby the raising of a magazine is prevented until the matrices are locked therein.

The invention will be clearly understood from the following description of forms which the invention may assume and the description will be more readily followed by reference to the accompanying drawings wherein:

Figure 1 is a side view of the relevant parts of a machine constructed according to the present invention showing the magazine supporting arm

in its extended position and operable for the withdrawal of the magazine immediately below the uppermost;

Figure 2 is a similar view to that of Figure 1 but with the extensible arm in the closed position 5 and showing only a portion of the mechanism;

Figure 3 is a plan view of part of the mechanism of Figures 1 and 2;

Figure 4 is a side view of a modified construction according to the invention; and 10

Figure 5 is a plan view of Figure 4.

Referring to Figures 1, 2 and 3 of the drawings, a column of four superposed magazines, 1, 2, 3 and 4 is illustrated, which column may be adjusted in well known manner to bring any selected magazine into operative position. The side frames between which the magazine column is adjustable, are provided with a pair of pivoted magazine supporting arms 5, 6, one at each side, and the supporting arm 5 on one of the side 15 frames is fixed to a rock shaft 7 mounted in the frame. This shaft 7, hereinafter termed the supporting arm shaft, is adapted to operate two arms 8 and 9 connected to links 10, 11 which respectively effect the spread of the magazines and the 20 separation of the selected magazine from its base frame. The arms 8 and 9 are provided with slots 8a and 9a respectively by means of which they are positioned and guided on rollers 8b and 9b secured to the machine frame. It will be observed 25 that the arm 5, when in the operative position as shown in Figure 1, banks on the shoulder 5a in the machine frame.

The spreading of the magazines may be effected by means of a pair of links 12, 13 forming 35 a toggle at each side of the magazine column, the toggle being extended and collapsed by rocking a shaft 14 extending across the base frame of the lowest magazine, to which shaft, hereinafter termed the toggle shaft 14, one link 13 of each 40 pair is fastened, the other link 12 of each pair being pivotally connected to the base frame 15 of the uppermost magazine 1. There are also provided pairs of lifting hooks 16, 17 suspended from each side of the uppermost base frame, arranged 45 to be engaged as desired with studs 18 extending laterally from the base frames of the magazines 2, 3, 4 below the uppermost. The lifting hooks 16 and 17 are adjusted manually in relation to the studs 18.

In carrying out the present invention the toggle shaft 14 is at one end formed with a tongue 19 adapted to engage in a groove 20 formed in one or another of a series of levers 21 which are connected by means of a link 22 and simultaneously 50 55

operated by the beforementioned link 10 connected to the supporting arm shaft 7, by means of the arm 8, the arrangement being such that as the magazine column is adjusted the toggle shaft 14 is operatively connected with the grooved levers 21 in succession. The movement of the link 10 by the arm 8 is limited by the stop 10a.

In order to separate the selected magazine from its base frame to facilitate removal of the magazine therefrom, the above-mentioned link 11, operable by the supporting arm shaft 7 through the arm 9, is connected with an arm 23 fast on a shaft 24 formed with a groove 25 adapted to engage with a tongue 26 on a transverse shaft 27 mounted on the base frame 15 of each magazine. A shaft 27 is provided for each base frame. By these connections, when the supporting arm shaft 7 is rocked, the transverse shaft 27 on the base frame 15 of the selected magazine is also rocked to operate a cam member 28 for raising the respective magazine from the base frame. The link 11 tends to be held against the stop 11a by the pull of the spring 32 (Figure 2).

The cam member 28 is provided with a notch 29 which is adapted to engage the pin 30 in the plate 31 which is pivoted to the base frame 15 of the second magazine as shown in Figure 1. The cam member 28 is as shown in Figure 3 in the form of a flat plate which is adapted to engage in a recess formed in the upper side of the base frame when in the inoperative position.

The arm 8 is provided at the end nearest to the supporting arm shaft 7 with a hook end 33. A lever 34 is fixed on the shaft 7 at the end of which is a stud 35 which is adapted to engage in the hook end 33 and actuate the lever arm 8. A stud 36 is also provided on the arm 5 which engages in a hook end 37 formed in the end 38 of the lever arm 9. Upon movement of the arm 5 from the position shown in Figure 2 to that of Figure 1 the arm 8 is first actuated and through it the magazine spreading mechanism constituted by the toggle linkage 12, 13 and the lifting hooks 16, 17 by means of the levers 21 and the link 22 operating the shaft 14. When the spreading movement is complete the stud 35 leaves the hook end 33 and the spread magazine frames hold the lever 10 against the stop 10a by their own weight. The stud 36 is positioned in relation to the hook end 37 of the arm 9 so that the arm 9 with its associated separating mechanism is actuated after the arm 8 and its associated magazine spreading mechanism and it will be apparent that the arrangement is such that a magazine cannot be raised from a base frame until the magazine frames have been separated.

It is to be noted that when the supporting arm 5 is in the inactive position, the grooves 20 in the levers 21 of the spreading mechanism and the groove 25 on the arm 23 of the separating mechanism are aligned respectively with the tongue 19 on the toggle shaft 14, and the tongues 26 on the transverse shafts 27 of the several base frames 15, so that as the magazine column is moved to the different positions bringing the magazines 2, 3 and 4 into operative position relative to the assembler entrance 39 the respective tongues and grooves are brought into engagement. However, as no spreading of the magazines is needed when the uppermost magazine is in the removal position, it is unnecessary to provide a magazine spreading lever 21 for operating the toggle shaft 14 when the magazine column is in its lowermost position.

A modification of the invention will now be described with reference to Figures 4 and 5 in which the arrangement of the spreading and separating mechanism is in all material respects identical with that described with reference to Figures 1, 2 and 3. Figures 4 and 5, however, illustrate the invention applied to a different form of magazine and in conjunction with means for preventing the lifting of a magazine until all the matrices are locked therein. In Figures 4 and 5 the magazines are again shown at 1, 2, 3 and 4 and reference numerals corresponding to those used in Figures 1 to 3 are used to indicate parts of the spreading and separating mechanisms which are substantially identical with those previously described. It is to be noted however that the slots and rollers 8a, 8b, 9a, 9b shown in Figure 1 are not employed and the arms 8 and 9 are guided by means of rollers 40 and 41 which run in radial races 42 and 43 secured about the supporting arm shaft 7.

The device for preventing the raising of a magazine until all the matrices are locked therein consists of a stud 44 on the arm 5 which engages with a recess 45 in the arm 46. The arm 46 is held in such a position that the stud 44 remains in engagement with the recess 45 by means of the lever 47. When the escapement locking pawl is released the lever 47 is free to move under the influence of the spring 49 so that the arm 46 can be moved manually to free the supporting arm 5.

It is further to be noted in connection with the constructional forms of the invention above described, that although, as is usual, a magazine supporting arm is provided at each side of the machine, the spreading and separating connections described need be associated with only one of the said arms, the other arm being simply adjustable on the other side frame between its active and inactive positions.

Having described our invention, we declare that what we claim and desire to secure by Letters Patent is:

1. A typographical composing machine of the kind referred to including in combination a plurality of magazines, each of said magazines being mounted on a base frame, an extensible arm for supporting one of said magazines on removal or replacement, and mechanism actuated by the adjustment of said arm to the magazine supporting position for spreading the magazines and for separating from its base frame the magazine to be removed.

2. A typographical composing machine of the kind referred to including in combination a plurality of magazines adjustable to bring a selected magazine into operative position, each of said magazines being mounted on a base frame, an extensible arm for supporting one of said magazines on removal or replacement, and mechanism associated with said magazines and arranged to be connected automatically with the selected one thereof for spreading the magazines and for separating said selected magazine from its base frame, said mechanism being actuated by the adjustment of said extensible arm to the magazine supporting position.

3. A typographical composing machine of the kind referred to including in combination a plurality of magazines, each of said magazines being mounted on a base frame, an extensible arm for supporting one of said magazines on removal or replacement, and mechanism for successively spreading the magazines and separating from its

base frame the magazine to be removed, said mechanism being actuated by adjustment of said extensible arm to the magazine supporting position.

5 4. A typographical composing machine of the kind referred to including in combination a plurality of magazines, each of said magazines being mounted on a base frame, an extensible arm for supporting one of said magazines on removal or replacement, mechanism actuated by the adjustment of said arm to the magazine supporting position for spreading the magazines and for separating from its base frame the magazine to be removed, and means for ensuring that a magazine cannot be lifted from its base frame until the magazine frames have been spread.

10 5. A typographical composing machine of the kind referred to including in combination a plurality of magazines adjustable to bring a selected magazine into operative position, each of said magazines being mounted on a base frame, an extensible arm for supporting one of said magazines on removal and replacement, and mechanism for successively spreading the magazines and separating from its base frame the magazine to be removed, said mechanism being actuated by adjustment of said extensible arm to the magazine supporting position, said spreading and separating mechanism being arranged to be automatically connected upon the selected magazine being brought to the operative position.

15 6. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism actuated by the adjustment of said arm to the magazine supporting position for spreading the magazines and for separating from its base frame the magazine to be removed, and means for ensuring that a magazine cannot be lifted from its base frame until the magazine frames have been spread, said spreading and separating mechanism being arranged to be automatically connected upon the selected magazine being brought to the operative position.

20 7. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism actuated by the adjustment of said arm to the magazine supporting position for spreading the magazines and for separating from its base frame the magazine to be removed, and operating devices included in said mechanisms arranged to be connected automatically as the selected magazine is moved into operative position.

25 8. A typographical composing machine of the kind referred to including in combination a plurality of magazines, each of said magazines being mounted on a base frame, an extensible arm for supporting one of said magazines on removal or replacement connected to a rock shaft, operating devices for spreading the magazines and for separating from its base frame the magazine to be removed, and an arm and linkage connecting said rock shaft with said operating devices.

30 9. A typographical composing machine of the kind referred to including in combination a plurality of magazines adjustable to bring a selected

magazine into operative position, each of said magazines being mounted on a base frame, an extensible arm for supporting one of said magazines on removal and replacement, a rock shaft connected to said arm, an arm and linkage connecting said rock shaft to operating devices for spreading said magazines and separating a magazine from its base frame, and mechanism associated with the selected magazine and arranged to connect automatically with one of said operating devices as said magazine is brought into operative position.

35 10. A typographical composing machine of the kind referred to including in combination a plurality of magazines, each of said magazines being mounted on a base frame, an extensible arm for supporting one of said magazines on removal and replacement, and mechanism for successively spreading the magazines and for separating from its base frame the magazine to be removed, said mechanism including a spreading arm and a separating arm each having hooked ends, said extensible arm having a stud thereon to engage with the hook of the spreading arm and a stud on said arm to engage in the hook of the separating arm.

40 11. A typographical composing machine of the kind referred to including in combination a plurality of magazines adjustable to bring a selected magazine into operative position, each of said magazines being mounted on a base frame, an extensible arm for supporting one of said magazines on removal and replacement, a rock shaft connected to said arm, operating devices for spreading said magazines, operating devices for separating a magazine from its base frame, mechanism associated with the selected magazine and arranged to connect automatically with one of said operating devices as said magazine is brought into operative position, linkage connected to each operating device, a spreading arm and a separating arm respectively connected to said operating devices, said arms being provided with hooked ends, a lever pivoted to said rock shaft having a stud thereon adapted to engage in the hooked end of the spreading arm and disengage therefrom upon spreading being completed, and a stud on the extensible arm adapted to engage in the hooked end of the separating arm.

45 12. A typographical composing machine of the kind referred to including in combination a plurality of magazines, each of said magazines being mounted on a base frame, an extensible arm for supporting one of said magazines on removal or replacement, and mechanism actuated by the adjustment of said arm to the magazine supporting position for spreading the magazines and for separating from its base frame the magazine to be removed, said mechanism including operating devices having tongue and groove connection with an operative shaft of the corresponding magazine.

50 13. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism actuated by the adjustment of said arm to the magazine supporting position for spreading the magazines and for separating from its base frame the magazine to be removed, and operating devices included in said mechanisms

arranged to be connected automatically as the selected magazine is moved into operative position, said operating devices having tongue and groove connection with an operative shaft of the corresponding magazine arranged to be connected automatically upon said magazine being moved into the operative position.

14. A typographical composing machine of the kind referred to including in combination a plurality of magazines, each of said magazines being mounted on a base frame, an extensible arm for supporting one of said magazines on removal or replacement, and mechanism actuated by the adjustment of said arm to the magazine supporting position for spreading the magazines and for separating from its base frame the magazine to be removed, said spreading mechanism including a lever associated with each magazine except the uppermost, said levers being adapted to engage successively with a toggle shaft, said toggle shaft having secured thereto a toggle linkage and lifting hooks engaging studs on said magazines actuated by said toggle linkage.

15. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism for spreading the magazines actuated by adjustment of said extensible arm to the magazine supporting position, said spreading mechanism including a lever associated with each magazine except the uppermost, said levers being adapted to engage successively with a toggle shaft, said toggle shaft having secured thereto toggle linkage, lifting hooks engaging studs on said magazines adapted to be actuated by said toggle linkage, said levers being arranged to be connected automatically with said toggle shaft as the selected magazine is moved into operative position, and mechanism for separating from its base frame the magazine to be removed.

16. A typographical composing machine of the kind referred to including in combination a plurality of magazines, each of said magazines being mounted on a base frame, an extensible arm for supporting one of said magazines on removal or replacement, and mechanism actuated by the adjustment of said arm to the magazine supporting position for spreading the magazines and for separating from its base frame the magazine to be removed, said separating mechanism comprising a plate pivoted to each magazine base frame, said plate being movable about its pivot by mechanism operated by said extensible arm.

17. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism actuated by the adjustment of said arm to the magazine supporting position for spreading the magazines and for separating from its base frame the magazine to be removed, said separating mechanism comprising a plate pivoted to a shaft on each magazine base frame, said shaft having a tongue therein engaging a groove in a lever actuated by said extensible arm, said groove being arranged to be connected automatically with the shaft of the selected maga-

zine as said magazine is moved into the operative position.

18. A typographical composing machine of the kind referred to including in combination a plurality of magazines, each of said magazines being mounted on a base frame, an extensible arm for supporting one of said magazines on removal or replacement, mechanism actuated by the adjustment of said extensible arm to the magazine supporting position for spreading the magazines and for separating from its base frame the magazine to be removed, and means for preventing movement of said extensible arm until the matrices have been locked in their channels.

19. A typographical composing machine of the kind referred to including in combination a plurality of magazines adjustable to bring a selected magazine into operative position, each of said magazines being mounted on a base frame, an extensible arm for supporting one of said magazines on removal or replacement, mechanism associated with said magazines and arranged to be connected automatically with the selected one thereof for spreading the magazines and for separating said magazine from its base frame, said mechanism being actuated by the adjustment of said extensible arm to the magazine supporting position, and means for preventing movement of said extensible arm until the matrices have been locked in their channels.

20. The combination according to claim 18 wherein a lever connected with the matrix locking means is formed with a recess adapted to engage a stud on the extensible arm.

21. A typographical composing machine of the kind referred to including in combination a plurality of magazines adjustable to bring a selected magazine into operative position, each of said magazines being removably mounted on a base frame, means associated with the selected magazine for separating it from its base frame preparatory to removal or replacement, means for spreading the magazines apart to permit the operation of said magazine separating means, and a common operating device for the two said means.

22. A typographical composing machine of the kind referred to including in combination a plurality of magazines adjustable to bring a selected magazine into operative position, each of said magazines being removably mounted on a base frame, means associated with the selected magazine for separating it from its base frame preparatory to removal or replacement, means for spreading the magazines apart to permit the operation of said magazine separating means, and a common operating device for the two said means, said device when operated acting first to spread the magazines and thereafter to separate the selected magazine from its base frame.

23. A typographical composing machine of the kind referred to including in combination a plurality of magazines adjustable to bring a selected magazine into operative position, each of said magazines being removably mounted on a base frame, means associated with the selected magazine for separating it from its base frame preparatory to removal or replacement, means for spreading the magazines apart to permit the operation of said magazine separating means, and a common operating device for the two said means, said device being mounted on a relatively fixed part of the machine and arranged to be automatically coupled to the magazine separating

and spreading means as the selected magazine is brought into operative position.

24. A typographical composing machine of the kind referred to including in combination a plurality of magazines adjustable to bring a selected magazine into operative position, each of said magazines being removably mounted on a base frame, means associated with the selected magazine for separating it from its base frame preparatory to removal or replacement, means for spreading the magazines apart to permit the operation of said magazine separating means,

and an extensible magazine supporting device mounted on a relatively fixed part of the machine and arranged when unextended to be automatically coupled to the magazine separating and spreading means as the selected magazine is brought into operative position, said device acting when extended first to spread the magazines and thereafter to separate the selected magazine from its base frame. 6
